(57) **CLAIM**

We claim the ornamental design for a bucket trap, as shown and described.

DESCRIPTION

FIG. 1 is a perspective view of a bucket trap showing our new design;

FIG. 2 is a top view thereof;

FIG. 3 is a bottom view thereof; and,

FIG. 4 is a side view thereof.

The bucket trap is shown with a symbolic break in its length. The appearance of any portion of the bucket trap between the break lines forms no part of the claimed design.
